UNITED STATES PATENT OFFICE.

JAMES WESLEY ROSS AND WILLIAM ARTHUR ORR, OF HAMILTON, ONTARIO, CANADA;
SAID ORR ASSIGNOR TO SAID ROSS.

DESIGN FOR A HEADLIGHT LENS.

60,374.

Specification for Design.

Patented Feb. 7, 1922.

Application filed April 11, 1921. Serial No. 460,512. Term of patent 7 years.

To all whom it may concern:

Be it known that we, JAMES WESLEY Ross and WILLIAM ARTHUR ORR, both subjects of the King of Great Britain, and residents of the city of Hamilton, in the county of Wentworth, in the Province of Ontario, Dominion of Canada, have invented a new, original, and ornamental Design for a Headlight Lens, of which the following is a specification, reference being had to the accompanying drawing, forming part thereof.

The figure is a front view of a headlight lens constructed according to our new design.

The upper part of the lens is clear and transparent while the lower part is translucent.

The curved dividing line extending across the lens is formed of three arcs of circles each of radius equal to one-sixth of the outside diameter of the lens.

The central arc is concentric with the lens and the outer arcs are both tangent to this central arc, to the outside circumference of the lens, and also to the horizontal diameter of the lens.

We claim:

The ornamental design for a headlight lens, as shown.

JAMES WESLEY ROSS.
WILLIAM ARTHUR ORR.
